UNITED STATES PATENT OFFICE

155,333

DESIGN FOR A LOUD-SPEAKER

John E. Currie, Brooklyn, and Willy Borberg,
Astoria, N. Y., assignors to International Pro-
jector Corporation, a corporation of Delaware

Application September 23, 1948, Serial No. 148,726

Term of patent 14 years

(Cl. D26—14)

To all whom it may concern:

Be it known that we, John E. Currie, a citizen of the United States of America residing at Brooklyn, county of Kings, State of New York, and Willy Borberg, a citizen of Germany, continuously a resident of the United States since September 1929, residing at Astoria, county of Queens, State of New York, have jointly invented a new, original, and ornamental Design for a Loud-Speaker, of which the following is a specification, reference being had to the accompanying drawing, forming a part thereof, in which

Fig. 1 is a top plan view of the loud-speaker, illustrating my new design;

Fig. 2 is a front elevational view thereof;

Fig. 3 is a rear elevational view thereof;

Fig. 4 is a side elevational view thereof looking

from the right in Fig. 2, both sides being identical, and

Fig. 5 is a perspective view of the device.

We claim:

The ornamental design for a loud-speaker, as shown and described.

JOHN E. CURRIE.
WILLY BORBERG.
